BATH MAT OR SIMILAR ARTICLE

Joseph C. Breneman, Wooster, Ohio, assignor to Rubbermaid Incorporated, Wooster, Ohio, a corporation of Ohio

Filed Aug. 11, 1960, Ser. No. 61,700

Term of patent 14 years

(Cl. D9—6)

FIG. 1

FIG. 3

Fig. 1 is a top plan view of a bath mat or similar article embodying my new design. The elements are illustrated only on part of the mat. It is to be understood that said elements cover the entire areas shown.

Fig. 2 is an enlarged fragmentary view of the lower center portion of Fig. 1; and

Fig. 3 is a sectional view taken along lines 3—3 of Fig. 2.

I claim:

The ornamental design for a bath mat or similar article, substantially as shown and described.
